CLAIM

The ornamental design for a holster for a steering wheel locking club, as shown and described.

DESCRIPTION

FIG. 1 is a top, front and left side perspective view of a holster for a steering wheel locking club showing my new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof; and,

FIG. 7 is a bottom plan view thereof.

The broken-line disclosure of a steering wheel locking club is for illustrative purposes only and forms no part of the claimed design.
